UNITED STATES PATENT OFFICE

100,111

DESIGN FOR A DRAWER PULL

Fred W. McCormick and Frederick C. Ruppel,
Grand Rapids, Mich.; said Ruppel assignor to
said McCormick

Application April 17, 1936, Serial No. 62,186

Term of patent 7 years

To all whom it may concern:

Be it known that we, Fred W. McCormick and Frederick C. Ruppel, citizens of the United States, residing at the city of Grand Rapids, in the county of Kent and State of Michigan, have invented a new, original, and ornamental Design for Drawer Pull, of which the following is a specification, reference being had to the accompanying drawing, forming a part thereof.

Fig. 1 is a plan view of a drawer pull showing my new design.

Fig. 2 is a side elevation of the same, and
Fig. 3 is an end elevation of the same.

We claim:

The ornamental design for a drawer pull as shown.

FRED W. McCORMICK.
FREDERICK C. RUPPEL.
